CLAIM

The ornamental design for side cover of construction machine, as shown and described.

DESCRIPTION

FIG. 1 is a front side (exterior) elevation view of right hand side cover for a construction machine showing our new design;
FIG. 2 is a rear side (interior) elevation view thereof;
FIG. 3 is a top view thereof;
FIG. 4 is a bottom view thereof;
FIG. 5 is left hand end view thereof;
FIG. 6 is right hand end view thereof;
FIG. 7 is an elevated perspective view thereof;
FIG. 8 is a reference picture to illustrate a cross section thereof through a line X-X in FIG. 1; and,
FIG. 9 is a reference picture to illustrate a cross section thereof through a line Y-Y in FIG. 1.
